**TRAY FOR RELEASEABLY ENGAGING A RAZOR
AND A BLADE CARTRIDGE DISPENSER**

Martin Glaberson, Ardsley, N.Y., assignor to Warner-Lambert Company, Morris Plains, N.J.

Continuation-in-part of design application Ser. No. 191,952, Oct. 22, 1971. This application Dec. 2, 1971, Ser. No. 204,413

Term of patent 14 years

Int. Cl. D9—03

U.S. Cl. D9—186

Fig. 1.

Fig. 2.

Fig. 3.

Fig. 6.

Fig. 5.

Fig. 4

FIG. 1 is a perspective view of a tray for releasably engaging a razor and a blade cartridge dispenser showing my new design;

FIG. 2 is an end elevation view thereof;

FIG. 3 is another end elevation view thereof;

FIG. 4 is a top plan view thereof;

FIG. 5 is a side elevation view thereof; and

FIG. 6 is a bottom plan view thereof.

The side view not shown is a mirror image of FIG. 5. This application is a continuation-in-part of design application Ser. No. 191,952, filed Oct. 22, 1971.

I claim:

The ornamental design for a tray for releasably engaging a razor and a blade cartridge dispenser, as shown and described.
